[57] ABSTRACT

Detergent compositions containing monoesters produced through esterifying dibasic or polybasic organic aliphatic carboxylic acids and/or dibasic or polybasic aromatic carboxylic acids with alcohols. These monoesters replace in the detergent previously used phosphates which caused eutrofication and endangered the ecology.

10 Claims, No Drawings

DETERGENT

BACKGROUND OF THE INVENTION

The present invention relates to washing, dish-washing and cleaning detergent compositions in the form of powders, granules, pastes, or liquids, in which the phosphates previously used in such detergents are completely or partly replaced by chemicals which are more suitable from the eutrophic point of view. The invention discloses the replacement of the phosphates which are undesirable from the eutrophic point in view by aliphatic carboxylic acids and/or their salts, such as lactic acid, acetic acid, tartaric acid and citric acid, or by aromatic carboxylic acids such as, e.g., benzoic acid, phthalic acid and tri-, tetra-, penta- and hexabenzene-carboxylic acids and/or their salts.

SUMMARY OF THE INVENTION

The present invention concerns the use of the salts of particularly the fruit acids as these have proved most suitable as substitutes for phosphates. The reason herefor is that they decompose easily biologically, forming few toxic substances, and they do not pollute lakes and rivers with phosphor or nitrogen.

DETAILED DESCRIPTION OF A PREFERRED EMBODIMENT

To increase the washing efficiency of these carboxylic acids it has proved suitable to let the carboxylic acids or part of the carboxylic acids incorporated in the detergent compositions react with lower alcohols to form monoesters. The alkaline salts of acid esters exhibit both lipophilic properties (alkyl groups) and hydrophilic properties (carbonyl group, $-\text{COONa}$). Since the dirt particles generally are embedded in fat these monoesters have proved suitable for use in a system consisting of mixture of fat and water wherein the alkyl group imparts the lipophilic properties to the molecule whereas the esterified $-\text{COOH}$ -groups impart the typical acid character to the molecule, i.e., its capability of forming complex heavy metal ions. Owing to the strengthened lipophilic property the dispersing and emulsifying properties of such compounds are heightened. The reason for the restriction to monoesters in this connection is that the higher esters are much less soluble and for this reason do not provide the same efficiency in detergents. In addition, the biological decomposability of the compound must be taken into consideration. Furthermore, the biological oxygen consumption, the so called, BO_5 -values, is lower in the case of monoesters than in the case of higher esters.

The esters are generally produced by esterifying the anhydrous acid with its respective alcohol and with a suitable catalyst or while using other suitable methods.

In the formulae given below X represents Na, K, or NH_4 and R the alcohol rest having one to eight carbon atoms.

Examples of monoesters:

1. Sodium ethylene dicarboxylic acid monoethyl ester $\text{Na}-\text{O}_2\text{C}-\text{CH}=\text{CH}-\text{CO}_2-\text{CH}_2\text{H}_5$
2. Potassium ethylene dicarboxylic acid monoethyl ester $\text{K}-\text{O}_2\text{C}-\text{CH}=\text{CH}-\text{CO}_2-\text{CH}_3$
3. Potassium ethylene dicarboxylic acid monobutyl ester $\text{K}-\text{O}_2\text{C}-\text{CH}=\text{CH}-\text{CO}_2-\text{C}_4\text{H}_9$

4. Sodium oxyethane dicarboxylic acid 1,4-monoethyl ester $\text{Na}-\text{O}_2\text{C}-\text{CH}_2-\text{CH}(\text{OH})-\text{CO}_2-\text{CH}_3$
5. Sodium oxyethane dicarboxylic acid monoisoamyl ester $\text{Na}-\text{O}_2\text{C}-\text{CH}_2\text{CH}(\text{OH})-\text{CO}_2-\text{C}_5\text{H}_{11}$
6. Ammonium ethane dicarboxylic acid monopropyl ester $\text{NH}_4-\text{O}_2\text{C}-\text{CH}_2-\text{CH}_2-\text{CO}_2-\text{C}_3\text{H}_7$
7. Potassium ethane dicarboxylic acid monoethyl ester $\text{K}-\text{O}_2\text{C}-\text{CH}_2-\text{CH}_2-\text{CO}_2-\text{C}_2\text{H}_5$
8. Sodium dioxo-succinic acid monomethyl ester $\text{Na}-\text{O}_2\text{C}-\text{CH}(\text{OH})-\text{CH}(\text{OH})-\text{CO}_2-\text{CH}_3$
9. Potassium dioxo-succinic acid monosecbutylester $\text{K}-\text{O}_2\text{C}-\text{CH}(\text{OH})-\text{CH}(\text{OH})-\text{CO}_2-\text{CH}(\text{CH}_3)\text{C}_2\text{H}_5$
10. Sodium 1,2,3-propene tricarboxylic acid monoethyl ester $\text{Na}-\text{O}_2\text{C}-\text{CH}_2-\text{C}(\text{CO}_2\text{H})-\text{CH}_2-\text{CO}_2-\text{C}_2\text{H}_5$
11. Ammonium tricarballyacid monohexylic ester $\text{NH}_4\text{O}_2\text{C}-\text{CH}_2-\text{CH}(\text{CO}_2\text{H})-\text{CH}_2-\text{CO}_2-\text{C}_6\text{H}_{13}$
12. Sodium-2-hydroxypropane tricarboxylic acid monoisoamylester $\text{Na}-\text{O}_2\text{C}-\text{CH}_2-\text{C}(\text{OH})-\text{CO}_2\text{H}-\text{CH}_2-\text{CO}_2-\text{C}_5\text{H}_{11}$
13. Potassium-2-hydroxypropane tricarboxylic acid monopropylester $\text{K}-\text{O}_2\text{C}-\text{CH}_2-\text{C}(\text{OH})-\text{CO}_2\text{H}-\text{CH}_2-\text{CO}_2-\text{C}_3\text{H}_7$

Naturally, the invention is not limited to the monoesters enumerated above but also other carboxylic acid monoesters which are harmless from a toxicological point of view may be used. One condition is, of course, that they are acceptable from a water-preservation point of view. In addition, they must give satisfactory washing results. Experiments have shown that to strengthen the efficiency of these esters it is advantageous to add polyvalent higher alcohols in amounts up to 25 percent, preferably between 0.5 and 8 percent, calculated on the amount of the above esters.

The anionic, amphoteric or nonionic surfactants which may be present in the detergents in accordance with the invention contain in their molecule at least one hydrophobic group having eight to 30 carbon atoms and a group making them water-soluble, this group being of anionic or nonionic character. Soaps, sulphonates, and sulphates are of importance as anionic active detergents. Also phosphate surfactants could be used. The sulphonates may be alkylaryl sulphonates, alkyl sulphonates, alkene sulphonates, oxyalkene sulphonates and oxyalkane sulphonates. Also sulphonated esters may be used. The sulphates may be, e.g., alkyl sulphate, fatty alcohol ether sulphate, sulphated amides of fatty acids, sulphated monoglycerides, sulphating products of ethoxylated and/or propoxylated fatty alcohols, alkyl phenols, fatty acid amides, and so on. Sulphonates of fatty acid esters of oxethane sulphonic acid and dioxyp propane sulphonic acid, fatty alcoholic esters of lower aliphatic and aromatic thiomono- and -dicarboxylic acids as well as condensation products of fatty acids with aminoethane sulphonic acids are useable. Synthetic, capillary-active carboxylates as well as condensation products of fatty acids with amino-carboxylic

acids or with protein hydrolysates as also phosphate esters of fatty alcohols and fatty acids may be used.

As nonionic surfactants may be used, e.g., alkyl phenols, fatty alcohols, alkyl amines, fatty acids and fatty acid alkylol amides, fatty amides polyglycol esters, phosphate esters of ethoxylated fatty alcohols, block polymerisates of ethylene oxide and propylene oxide, etc.

Also amphoteric surfactants may be used, such as imidazoline derivates of fatty acids, carboxybetaines, compounds with the phosphoric acid groups in the acid rest, or with sulphonic or sulphuric acid groups.

Foam stabilizers of foam inhibitors as well as corrosion inhibitors may be included and so may dirt-carrying substances, optical brighteners, perfumes, bactericides, enzymes, dyes, and water. Also different types of bleaching agents containing oxygen or chlorine and activators and stabilizers belonging thereto may be included.

In summary, all surfactants and aids used in connection with detergents and cleaning agents may be combined in accordance with the principle of the present invention and the enumeration given above is not to be considered as any restriction whatsoever.

The following examples illustrate the invention:

EXAMPLE 1

Detergent composition for ordinary washing, sprayed:

10 parts Na-dodecylbenzenesulphonate	30
5 parts fattyalcoholpolyglycolether	
7 parts zylenesulphonate	
2 parts sodiumsoap, 80%	
2 parts phosphateesters of ethoxylated fatty alcohol	35
15 parts sodium perborate	
15 parts sodium ethanedicarboxylicacidmonopropylester	
15 parts potassium-2-hydroxypropane tricarboxylicacid monoamylester	40
5 parts sodium citrate	
10 parts sodium silicate	
3 parts EDTA or NTA	
2 parts sodium salt of benzenetetracarboxylicacid	
9 parts CMC, optical brightener, magnesium silicate	45

EXAMPLE 2

Pre-washing detergent, powder, gran.

4 parts alkylsulphate, sodium salt	50
2 parts lauricacidmonoethanolamidethiosuccinicsemiester, sodium salt	
4 parts fattyacidpolyglycolester	
20 parts sodiumcarbonate, gran.	55
20 parts sodiumbicarbonate	
15 parts sodium disilicate	
20 parts sodium monoisoamyl-2-hydroxypropane tricarboxylicacidester	
5 parts sodium ethanedicarboxylicacid monoethyl ester	60
4 parts pentaerythritol	
6 parts CMC, optical brightener, enzymes, water	

EXAMPLE 3

Small-washing detergent, gran.

12 parts alkylbenzenesulphonate, 50%	65
6 parts fattyalcoholpolyglycolether	

3 parts thiosuccinicacidsemiester of fatty acid polyglycolether, sodium salt	
2 parts coconutfattyacidmonoethanolamide or fatty acidamidepolyglycolether	
6 parts sodium silicate	
2,5 parts mannitol	
16 parts sodium citrate	
5 parts sodium monobutyl benzenehexacarboxylicacidester	
3,5 parts benzenehexacarboxylic acid	
10 parts sodium carbonate, gran.	
14 parts sodium sesquicarbonate	
13 parts sodium sulphate calc.	
7 parts optical brightener, perfume, water	

EXAMPLE 4

Large-scale detergent, gran.

12 parts fatty alcoholpolyglycolether having 30 mols EO (ethylene oxide)	
2 parts tallowfattyalcohol	
3 parts cumolsulphonate	
10 parts sodium ethylenedicarboxylicacid-monoethyl ester	
5 parts Potassium ethylenedicarboxylicacid monomethylester	
5 parts sodium acetate	
20 parts sodium carbonate, calc.	
10 parts sodium bicarbonate	
15 parts sodium percarbonate	
10 parts sodium disilicate	
8 parts CMC, perfume, optical brightener, magnesium silicate, enzymes, and water	

EXAMPLE 5

Large-scale detergent, powder

6 parts dodecylbenzenesulphonate, calculated as containing 100%	
5 parts alkylphenolpolyglycolether, turbidity point 70°-74°C	
1 part fattyaciddiethanol amide	
2 parts Na-toluene sulphonate	
6 parts sodium soap	
20 parts sodium perborate	
10 parts K-1.2.3.-propenetricarboxylicacid monobutylester	
20 parts sodium dioxysuccinicacid monomethylester	
5 parts sodium tripolyphosphate	
4 parts d-sorbitol	
10 parts sodium silicate, cryst.	
11 parts CMC, perfume, optical brightener, enzymes, and water	

EXAMPLE 6

Machine Dish-washing detergent

3 parts polypropylene-ethylene oxide-addition product	
3 parts sodium alkylpolyglycoletherphosphate	
25 parts sodium acetate	
25 parts sodium sulphate	
15 parts sodium monoethyltricarballylacid monohexyl ester	
15 parts sodium monomethyl-2-hydroxypropane tricarboxylic acid ester	
14 parts perfume, dyes, bactericides, water	

EXAMPLE 7

Washing and cleaning paste
 10 parts fattyacidimidazolinederivate, 50%
 3 parts succinic acid-2-ethyl hexylicmonoester
 3 parts undecyleneacidmonoethanolamide
 16 parts fattyacidcondensationproduct with methyl taurine.
 7 parts hexanediol
 6 parts sodium monoethyl ethenedicarboxylicacid-ester 10
 5 parts sodium oxyethanedicarboxylicacid 1.4.-monobutylester
 2 parts adipinic acid
 3 parts CMC
 45 parts water

EXAMPLE 8

Liquid washing and cleansing agent
 7 parts of a mixture of alkane and alkenesulphonates 20

I Detergent of Example 4

II Detergent on soap base, containing 10% tripolyphosphate and 20% Na-perborate

III Detergent synthetic, containing 30% tripolyphosphate and 25% Na-perborate

IV Detergent synthetic, containing 18% NTA, 10% tripolyphosphate and 20% Na-perborate

3 parts dialkylphenolpolyglycolether
 3 parts undecyleneacidmonoethanolamidethiosuccinicacidsemester, sodium salt
 2 parts fattyacidamineoxide
 3 parts pine-oil
 3 parts ethyldiglycol
 10 parts NH₄-monopropyl oxyethanedicarboxylicacidester
 2 parts sorbite
 67 parts water, perfume, dyes, ammonia, etc.

To show the effects of the detergent of Example 4 above as compared with known detergents containing phosphates and NTA the following washing test results are given:

TABLE 4

50	Coloured Washing	Incineration after 10 washes		
		Prewash 45°C/Main Wash 60°C	Test 1	Test 2
				Average Value
I		0.15%	0.12%	0.13%
II		0.06%	0.05%	0.06%
III		0.05%	0.05%	0.05%
IV		0.05%	0.05%	0.05%
 55				
60	White Washing	Prewash 40°C/Main Wash 85°C		
		Test 1	Test 2	Average Value
		0.08%	0.09%	0.09%
I		0.10%	0.08%	0.09%
II		0.07%	0.06%	0.07%
III		0.07%	0.05%	0.06%
IV		0.05%	0.05%	0.06%

Detergent Dosage	Prewash gr/k	Main Wash gr/k
I	6	26
II	6	24
III	6	25
IV	7	27

The above results show that the substitutes for phosphates and NTA as taught by the present invention provide a detergent possessing equally good washing results without increasing incrustation, as is apparent from Table 4. The detergent in accordance with the invention thus provides excellent washing results without

polluting the water recipients with nutrient salts containing phosphor and nitrogen.

What I claim is:

1. Detergent compositions for washing, dish-washing and cleaning purposes in the form of powders, pastes, or liquids, consisting essentially of water softeners, anionic and non-ionic detergents and detergent effect intensifiers, wherein said water softeners and said detergent effect intensifiers are monoesters produced through esterifying dibasic or tribasic organic aliphatic carboxylic acids having up to nine carbon atoms in the hydrocarbon moiety and/or dibasic or tribasic aromatic carboxylic acids with alcohols having one or several hydroxyl groups and one to eight carbon atoms in the hydrocarbon moiety, said monoesters being present in said detergent compositions in amounts of between 5 and 30 percent.

2. Detergent compositions as claimed in claim 1, wherein said carboxylic acids are oxycarboxylic acids.

3. Detergent compositions as claimed in claim 1, wherein the free carboxylic groups of said monoesters

are at least partly neutralized by means of alkalis.

4. Detergent compositions as claimed in claim 1, which contain monoesters.

5. Detergent compositions as claimed in claim 1, wherein said monoesters are a mixture.

6. Detergent compositions as claimed in claim 5, wherein said monoesters are a mixture together with the salts of said carboxylic acids.

7. Detergent compositions as claimed in claim 5, 10 wherein said monoesters are a mixture together with said free carboxylic acids.

8. Detergent compositions as claimed in claim 1, additionally containing polyvalent alcohols in amounts up to 25 percent calculated on said carboxylic acids.

15 9. Detergent compositions as claimed in claim 8, wherein said polyvalent alcohols are sorbitol, mannitol, pentaerythritol, trimethyl propanol, trimethyl ethanol, hexanetriol, butane-1.2.4-triol.

20 10. The detergent composition of claim 8, wherein the polyvalent alcohols are present in amounts of between 0.5 and 8 percent.
